MASS SPECTROMETRY

Harold W. Washburn, Pasadena, Calif., assignor
to Consolidated Engineering Corporation, Pasadena, Calif., a corporation of California

Application July 16, 1945, Serial No. 605,262

12 Claims. (Cl. 250—41.9)

1

This invention relates to the mass spectrometry and particularly to the ionization of molecules therein by bombardment with an electron beam. It provides improvements in apparatus for producing and controlling such a beam with the result that the distribution of electron energy in the beam is made more uniform, to the end that the efficiency of ionization is increased and the calibration of the spectrometer is less subject to deviation.

Essentially, a mass spectrometer is an apparatus for producing ions and sorting them according to mass-to-charge ratio, i. e. according to specific mass. A sample to be analyzed, for example a gas mixture, is ionized (for example, by bombarding its molecules with electrons) and the resulting ions are propelled as a heterogeneous beam by an electrical potential into a magnetic field in which the ions separate into a series of divergent homogeneous ion beams. The sorted ions are collected and discharged, the quantity of each kind of ions being measured by the amount of current that they discharge upon collection.

In certain more recent types of mass spectrometers, ionization is accomplished in a separate chamber, usually by bombarding molecules therein with a beam or stream of electrons and the resulting ions are propelled through slits in collimating electrodes into an analyzer by potentials maintained between the electrodes.

The electron beam employed to ionize the molecules in the ionization chamber conveniently originates at an electron source, such as a heated filament; and electrons of the beam are propelled across a space within the ionization chamber toward a catcher electrode. A very small portion (say 1 in 10,000) of the electrons in the beam are consumed in the ionization of molecules with which they collide in their movement within the ionization chamber; the balance pass to the catcher. Many of the electrons lodge at the catcher and produce no secondary effects. Some (say half) of the electrons, upon striking the surface of the catcher, cause the throwing off of other electrons which rebound into the electron beam to the electron source, where they strike and may cause further secondary emissions of electrons. In this way, electrons of various energy contents are, in effect, "bounced" back and forth in the electron beam between the source and the catcher, especially if electrons are held in this path by a magnetic field which encompasses both the ionization chamber and the analyzer.

I have discovered that this "bouncing" or "re-

fection" of electrons due to the secondary emission effects just described, has a deleterious effect upon the mass spectrogram produced by the instrument and tends to cause erroneous and erratic results. Thus the secondary emissions originating at the catcher tend to produce a non-uniform distribution of electrons and of electron energy within the beam, and these non-uniformities in turn affect (1) the efficiency of ionization and (2) the peak pattern or spectrogram produced, since the effects of secondary emission are different at each peak.

In accordance with my invention, the secondary emissions are prevented from bouncing back into the electron beam within the ionization chamber (and thus tertiary, quaternary, etc. emissions are also prevented) by disposing a secondary emission suppressor electrode in the path of the electron beam between the source and the catcher but adjacent the latter and at or near the potential of the former. Conveniently, the suppressor electrode is provided with an aperture disposed coaxially with a straight line drawn from the electron source to catcher, i. e. in line with the two, so that the electron beam passes through the aperture.

Generally speaking, the most convenient way of achieving correct polarity and potential for the suppressor electrode is to connect it directly through a low-resistance lead to the positive side of the filament which acts as an electron source. However, on occasion it may be desirable to have the suppressor electrode slightly positive with respect to the electron source and this may be accomplished by inserting a small bias battery or other D. C. current source in the circuit connecting the electron source to the suppressor electrode. Less frequently, it may be desirable to make the suppressor electrode slightly negative with respect to the electron source, and this can be accomplished by switching the polarity of the bias voltage or by inserting another bias battery of reversed polarity.

In the preferred structure of my invention both the electron source (filament) and the catcher are mounted outside the ionization chamber and the electron beam passes from one to the other through apertures in the walls of the chamber. The beam thus passes transverse to the direction in which the ions are propelled from the ionization chamber to analyzer and parallel to the lines of force between the poles of an electromagnet which brings about sorting of the ions.

Preferably, also, the suppressor electrode is

3

located outside the ionization chamber proper, as by being mounted within a separate chamber in which the catcher is also disposed. This separate chamber conveniently is cut in the wall of the ionization chamber itself.

These and other features of my invention will be understood more thoroughly in the light of the following detailed description, taken in conjunction with the accompanying drawings in which:

Fig. 1 is a schematic diagram of a mass spectrometer of a type to which the invention is applicable;

Fig. 2 is a schematic transverse section through the head of the mass spectrometer of Fig. 1, taken along the line 2-2, with an associated wiring diagram showing the electrical connections of filament, catcher and the secondary emission suppressor;

Fig. 3 is a graph showing the relationship of peak height to catcher voltage and catcher current in a mass spectrometer when no secondary emission suppressor is employed;

Fig. 4 shows the relationship of the catcher voltage and catcher current in the same mass spectrometer employing a secondary emission suppressor in accordance with the invention.

Referring now to Fig. 1, it will be seen that the apparatus comprises a cylindrical head or block 10, the rear of which connects with a gas inlet tube 11 made of insulating material. Within the head there is an inlet or pusher electrode 12 in the form of a metallic plate insulated from the rest of the apparatus.

An electron beam 13 is produced within the head in the space immediately below the pusher electrode as described in greater detail hereinafter.

The space in the head through which the electron beam passes is known as the ionization chamber 14. The front or lower portion of the ionization chamber is formed by a collimating electrode 15 which is electrically connected to the head or block and is provided with a slit S₁ that is substantially in line with the pusher electrode and with the path of the electron beam. A second collimating electrode 16 is provided with a second slit S₂ in line with the slit S₁ and the electron beam is spaced below the first collimating electrode by a ring 17 of insulating material. The head of the apparatus is connected to an analyzer tube 18 through the slit S₂. The analyzer tube is bent in a semi-circle and encloses an analyzing chamber 19.

In the operation of the apparatus, a sample of gas to be analyzed is admitted into the gas inlet tube and passes into the space below the pusher electrode where it is bombarded by the electron beam. Molecules of the gas sample are thus ionized and the resulting ions are propelled as an unsorted ion beam by the pusher electrode through the slits S₁, S₂ in the collimating electrodes into the analyzer tube. There the unsorted beam is separated into a plurality of diverging homogeneous ion beams B₁, B₂, B₃ by means of a magnetic field produced in the head of the apparatus as well as in the analyzer tube by an electromagnet (not shown in Fig. 1).

Any one of the diverging ion beams may be focused on an exit slit 20 at the end of the analyzer tube so that it passes therethrough and strikes an ion collector 21. The current thus established in the ion collector is amplified and recorded by suitable amplifying and recording apparatus 22 and serves as an index of the quan-

4

tity of the particular type of ions collected from the sample.

The head 10 of the mass spectrometer and attached analyzer tube 18 are enclosed within an envelope 23 through the wall of which the sample inlet tube 11 projects. A high degree of vacuum is maintained within the envelope by means of vacuum pumps (not shown) connected to the envelope. Electrical circuits which produce the propelling potentials within the head of the mass spectrometer are shown at the left of Fig. 1. A battery or other direct current supply 30 is connected to the ends of a potentiometer 31. The positive end of this potentiometer and its slider are connected through a switch 32 to a condenser 33. A potential dividing network is connected across this condenser and takes the form of a resistance or potentiometer 35 connected at its negative end to ground.

The pusher electrode 12 is connected to the positive side of the network. The first collimating electrode 15 is connected to the slider of the potentiometer 35 and the second collimating electrode 16 is connected to the negative end of the network and to ground.

The position of the ion beams B₁, B₂, B₃ with respect to the exit slit may be changed either by varying the magnetic field or the propelling potentials. The latter method is preferred and may be practiced as follows:

The switch 32 in the energizing network is closed and the condenser 33 is charged to an appropriate level. Then the switch is opened and the condenser is permitted to discharge through the potential dividing network and the several electrodes in the head of the spectrometer. In this way the propelling potentials between the several electrodes gradually decay while maintaining relative values.

It will be observed that the potentials in the head may be adjusted relative to each other by suitably setting the potentiometer. In this way the ion beam may be adjusted to give optimum results at the exit slit and the ion collector.

Referring now to Fig. 2, the head of the spectrometer is shown in a section taken along the line 2-2 of Fig. 1. Conveniently, the head is a thick-walled metallic cylinder of "Nichrome" or the like and encloses the cylindrical ionization chamber 14. One side of the head has a cut-out portion within which an electron gun comprising a filament 40 and an electron accelerating electrode 41 are mounted. A closed chamber 42 is cut into the wall of the head on the opposite side and encloses a metallic catcher electrode 43 with a secondary emission suppressor 44 mounted in front of it. The electron beam 13 produced at the filament passes through an aperture 45 in the electron accelerating electrode and thence through an aperture or gun barrel 46 in the block into the ionization chamber. The electron beam passes parallel to and above the first slit S₁ in the collimating electrode 15 through a second aperture 47 in the block or head, thence through an aperture 48 in the secondary emission suppressor and strikes the catcher 43.

The filament, the electron accelerating electrode, the catcher and the secondary emission suppressor are insulated from each other and from the head.

As indicated hereinbefore, the head of the mass spectrometer as well as its analyzer tube are mounted between the poles of an electromagnet shown diagrammatically in Fig. 2. Thus,

magnet poles 50, 51 are so disposed with respect to the head that the direction of the magnetic lines of force (indicated at 52) is parallel to the path of the electron beam 13.

To understand the manner in which the electron beam is produced and controlled, reference should be made to the wiring diagram in Fig. 2. A direct current source 60 produces current and potential for the filament 40 of the electron gun with which it is connected through a variable resistor 61. A center tap resistor 62 is connected by its ends across the circuit adjacent the filament. The positive end of the filament may be connected directly to the secondary emission suppressor 44 through a triple throw switch 63. However, if it is desired to make the secondary emission suppressor slightly positive with respect to the filament, the triple-throw switch may be thrown to cut in a small direct current source 64, i. e. a bias battery. It may be desirable to make the secondary emission suppressor slightly negative with respect to the filament, in which case the triple-throw switch will be thrown to cut in another small direct current source or bias battery 65, the polarity of which is reversed with respect to current sources 60, 64. The catcher 43 is connected into the circuit through a microammeter 66 and a direct current source 67 to the center tap of the resistor 62. In this way, a potential difference to further the flow of electrons is maintained between the catcher and the filament.

Energy and potential for the electron accelerating electrode 41 is supplied by a direct current source 68 connected to the accelerating electrode through a milliammeter 69 and to the center tap of the resistor 62. It is shunted by a voltmeter 70.

A so-called "ionizing potential" maintained between the filament and the block is supplied by a direct current source 71 connected to the slider of the potentiometer 62 and to the block or head 10 through a microammeter 72. This current source is shunted by a voltmeter 73.

In the operation of the mass spectrometer electrons produced by heating of the filament 40 are projected as a beam through the ionization chamber to the catcher. When the electrons strike the surface of the catcher, there is a tendency for them to throw off electrons of less energy and because of the direction of the magnetic lines of force, the secondary emission thus produced tends to be driven backward as a stream of electrons toward the filament. Some of these secondarily emitted electrons may strike the filament and set up further tertiary, etc. emissions at that point with the result that electrons are bounced back and forth in the beam between the filament and the catcher. This result, if it were permitted to prevail, would change both the distribution of electrons and electron energy in the cross-section of the beam and would make the distribution of electron energy most erratic. Ionization efficiency depends upon having a uniform energy content for the electrons, so it is apparent that the effect of secondary emission upon ionization efficiency is deleterious.

To prevent secondary emission, the secondary emission suppressor 44 is interposed between the catcher and the filament and adjacent the former. By maintaining the potential of the suppressor at or close to the potential of the filament, any secondarily emitted electrons are caught by the suppressor and not permitted to

enter the ionization chamber in countercurrent to the main stream of electrons.

As indicated hereinbefore, it will usually be desirable to maintain the secondary emission suppressor at the same potential as the filament. Occasionally, however, it may be desirable to make the suppressor slightly positive with respect to the filament and less occasionally, slightly negative with respect to it. All three of these results can be accomplished with the triple-throw switch 63 and auxiliary current sources 64, 65.

The deleterious effect of secondary emissions from the catcher of a mass spectrometer when no suppressor is employed are illustrated in Fig. 3 whereon catcher voltage is plotted as the abscissa and peak height and catcher current on the ordinate. In Fig. 3, it will be observed that catcher current varies markedly with catcher voltage, indicating that as the voltage is changed, the amount of secondary emission from the catcher varies quite erratically. The same may be said with respect to peak height which varies erratically but somewhat inversely with catcher current as catcher voltage is raised. Moreover, if a different gas is introduced, the shape of the curves becomes different, so that the effect upon the mass spectrum is altered and the calibration of the instrument is changed.

The height of the 58 peak was chosen for illustrative purposes. Curves with a variety of shapes have been observed with other peaks in the mass spectrum.

Fig. 4 shows the beneficial results obtained through the use of a secondary emission suppressor of the type illustrated in Fig. 2. Again, catcher voltage is plotted as the abscissa and height of the peak 58 and catcher current are plotted as ordinates. The effect of employing a suppressor which is slightly negative with respect to the filament is shown by the solid lines on Fig. 4. The effect of making the suppressor slightly positive with respect to the filament is shown by the dotted lines on Fig. 4. The curves for zero difference lie somewhere between the respective dotted and solid curves.

It will be observed that whether the difference between the filament and the suppressor is slightly positive or slightly negative beyond a certain catcher voltage, the effect of variation in catcher voltage upon peak height and catcher current becomes negligible, i. e. constant conditions of operation are obtained. This uniformity is obtained at lower catcher voltage when the suppressor is made slightly positive. However, since the catcher voltage is ordinarily quite high during operation, this advantage may be more theoretical than real.

I claim:

1. In a mass spectrometer having an ionization chamber, means for admitting molecules into the chamber, means for bombarding the molecules in the chamber with electrons to convert them into ions, and means for propelling the resulting ions out of the chamber and sorting them according to specific mass, the combination which comprises an electron source, an electron catcher, means for propelling the electrons as a beam between the source and the catcher, a suppressor electrode disposed substantially in the path of the electron beam adjacent the catcher, and means for maintaining the suppressor electrode at a potential that approximates that of the electron source.
2. In a mass spectrometer having an ioniza-

tion chamber, means for admitting molecules into the chamber, means for bombarding the molecules in the chamber with electrons to convert them into ions, and means for propelling the resulting ions out of the chamber and sorting them according to specific mass, the combination which comprises an electron source and an electron catcher disposed outside the chamber on opposite sides thereof but communicating therewith, means for propelling the electrons as a beam between the source and the catcher, a suppressor electrode disposed substantially in the path of the electron beam adjacent the catcher, and means for maintaining the suppressor electrode at a potential that approximates that of the electron source.

3. In a mass spectrometer having an ionization chamber, means for admitting molecules into the chamber, means for bombarding the molecules in the chamber with electrons to convert them into ions, and means for propelling the resulting ions out of the chamber and sorting them according to specific mass, the combination which comprises an electron source, and an electron catcher disposed outside the chamber on opposite sides thereof but communicating therewith through apertures in the wall of the chamber, means for propelling the electrons as a beam between the source and the catcher, means for producing in the region of the electron beam a magnetic field having lines of force passing in the same general direction as the beam, a suppressor electrode disposed substantially in the path of the electron beam adjacent the catcher, and outside the chamber, and means for maintaining the suppressor electrode at a potential that approximates that of the electron source.

4. Apparatus according to claim 3 in which the wall of the ionization chamber is metallic and the catcher and the suppressor electrode are located in a chamber cut into the wall of the ionization chamber.

5. In a mass spectrometer having an ionization chamber, means for admitting molecules into the chamber, means for bombarding the molecules in the chamber with electrons to convert them into ions, and means for propelling the resulting ions out of the chamber and sorting them according to specific mass, the combination which comprises an electron source, an electron catcher, means for propelling the electrons as a beam between the source and the catcher, means for producing in the region of the electron beam a magnetic field having lines of force passing in the same general direction as the beam, a suppressor electrode disposed substantially in the path of the electron beam adjacent the catcher and having an aperture concentric with a straight line drawn between the catcher and the source, and means for maintaining the suppressor electrode at a potential that approximates that of the electron source.

6. Apparatus according to claim 5 in which the source is located on one side of the chamber and communicates therewith through an aperture, and the suppressor electrode and the catcher are located outside the chamber on the side opposite the source and communicate with the chamber through an aperture coaxial with that through which the source communicates.

7. In a mass spectrometer having an ionization chamber, means for admitting molecules into the chamber, means for bombarding the molecules in the chamber with electrons to con-

vert them into ions, and means for propelling the resulting ions out of the chamber and sorting them according to specific mass, the combination which comprises an electron source, an electron catcher, means for propelling the electrons as a beam between the source and the catcher, a suppressor electrode disposed substantially in the path of the electron beam adjacent the catcher, and means for maintaining the suppressor electrode at a potential that is slightly positive with respect to the electron source.

8. In a mass spectrometer having an ionization chamber, means for admitting molecules into the chamber, means for bombarding the molecules in the chamber with electrons to convert them into ions, and means for propelling the resulting ions out of the chamber and sorting them according to specific mass, the combination which comprises an electron source, an electron catcher, means for propelling the electrons as a beam between the source and the catcher, a suppressor electrode disposed substantially in the path of the electron beam adjacent the catcher, and means for maintaining the suppressor electrode at a potential that is slightly negative with respect to that of the electron source.

9. In a mass spectrometer having an ionization chamber, means for admitting molecules thereinto, means for subjecting the molecules therein to electron bombardment to form ions and means for propelling the resulting ions from the chamber, the combination which comprises an electron source, an electron catcher, the source and catcher being so mounted with respect to the chamber that a straight line connecting them follows a substantially unobstructed path within the chamber, means for propelling electrons as a beam from the source to the catcher, means for producing in the region of the electron beam a magnetic field having lines of force passing in the same general direction as the beam, a suppressor electrode mounted in the path of the beam in the neighborhood of the catcher and having an aperture therein through which the beam passes and electrically connected to the electron source, and means for maintaining the source and the suppressor electrode at approximately the same potential.

10. Apparatus according to claim 9 in which the electron catcher and the suppressor electrode are mounted adjacent each other outside the ionization chamber, the latter being provided with an aperture through which the electron beam passes, this aperture being in line with the electron source, the catcher and the aperture in the suppressor electrode.

11. Apparatus according to claim 9 in which the electron catcher and the suppressor electrode are mounted adjacent each other in a second chamber formed in the wall of the ionization chamber.

12. In a mass spectrometer having an ionization chamber, means for admitting molecules into the chamber, means for bombarding the molecules in the chamber with electrons to convert them into ions, and means for establishing a potential gradient across the chamber to propel the resulting ions from the chamber, the combination which comprises an electron source, an electron catcher, means for propelling the electrons as a beam between the source and the catcher and transverse to the direction of the gradient, a suppressor electrode disposed substantially in the path of the electron beam adjacent

the catcher, and means for maintaining the suppressor electrode at a potential which approximates that of the electron source.
